UNITED STATES PATENT OFFICE.

CHARLES F. SPERY, OF CHICAGO, ILLINOIS, ASSIGNOR TO McCORD RADIATOR & MFG. CO., OF DETROIT, MICHIGAN, A CORPORATION OF MAINE.

RADIATOR.

Application filed June 21, 1926. Serial No. 117,252.

My invention relates to radiators and has among its other objects the production of devices of the kind described which are convenient, durable, efficient and satisfactory for use wherever found applicable.

A particular object of the invention is to provide an improved device of the kind described comprising sheet metal stampings which can be quickly and easily assembled 10 with each other.

Another particular object of the invention is to provide a radiator for an automobile or the like having improved means for causing the air passing through the 15 radiator to come into contact with all portions of the water tubes thereof.

Many other objects and advantages of the construction herein shown and described will be obvious to those skilled in the art 20 from the disclosure herein given.

To this end my invention consists in the novel construction, arrangement and combination of parts herein shown and described, and more particularly pointed out 25 in the claims.

In the drawings, wherein like reference characters indicate like or corresponding parts:

Fig. 1 is a fragmentary front elevation, 30 partly in section, of an automobile radiator embodying the invention;

Fig. 2 is a section taken on line 2—2 of Fig. 1;

Fig. 3 is a section taken on line 3—3 of 35 Fig. 1;

Fig. 4 is a section taken on line 4—4 of Fig. 2;

Fig. 5 is a side elevation of one of the 40 improved cooling fins of the radiator shown in Fig. 1; and

Fig. 6 is a fragmentary section taken through a radiator embodying another form of the invention.

Referring for the present to Figs. 1 to 5, 45 inclusive, wherein I have shown one form of the invention embodied in an automobile radiator designated generally by the reference character 10, the reference characters 12 and 13 designate the upper and lower tanks, respectively, of the radiator. The tanks 12 and 13 communicate with each other through a plurality of water tubes 14 which are preferably formed from relatively thin sheet metal and are preferably of

elongated cross section, as best shown in 55 Figs. 2 and 3. The tubes 14 are preferably formed with a seam 16 extending longitudinally of one edge thereof, the seam 16 being of the type generally termed "a single lock seam." It will be noted that each of the 60 tubes 14 is so formed that it tapers from each of its longitudinal edges to a line near the central portion of the tube. This aids in the exchange of heat from the water to the air flowing through the radiator. The 65 longitudinal edges are preferably arcuate as at 18, one arcuate edge 18 having the seam 16 formed therein. The seam 16 preferably projects outwardly from the tube so that 70 it may be quickly and easily soldered, or re-soldered if it becomes damaged in use.

The upper and lower ends of the tubes 14 preferably project through header plates 75 19 and are preferably soldered thereto, the plates being soldered or otherwise secured to the tanks 12 and 13. However, it is readily understood that in some instances I may prefer to dispense with the header plates 19 and solder the tubes 14 directly to the tanks 12 and 13.

Associated with the tubes 14 and preferably soldered thereto are a plurality of cooling fins 22 which in this embodiment of the invention are stamped from relatively thin sheet metal. The several fins 22 are substantially identical with each other and are arranged so that they give a honey-comb appearance to the radiator. Each of the tubes 14 has a pair of the fins 22 soldered thereto, each fin being soldered to one of 85 the pair of fins soldered to an adjacent tube 14.

Each of the fins 22 comprises a plurality of spaced portions 24 disposed substantially in the same plane, and a plurality of spaced portions 25 disposed in a substantially parallel plane. The portions 25 are disposed intermediate the portions 24 and are joined thereto by inclined portions 26. Formed in each portion 24 is a relatively large depression 28 adapted to accommodate one-half of the circumference of one of the tubes 14, a smaller depression 29 forming an extension of the depression 28 being adapted to receive one-half of the seam 16. The depressions 28 and 29 are best shown in Figs. 3 and 5, Fig. 5 being a view of one of the fins 22 looking at the side thereof in which the depressions

sions are formed. Rows of hollow buttons or projections 31 are preferably stamped in the portions 24 and 25 to facilitate the task of aligning the fins with each other during the assembly of the radiator, the construction being such that the projections formed upon one fin will extend into the projections formed upon the other fin (See Fig. 3). However, it is to be understood that in the preferred embodiment of the invention the fins are identical in construction and it is only necessary to reverse one of the fins with respect to another when it is desired to have the projections of one extend into the projections of the other.

Formed in the portions 25 are deflecting portions 33 which are adapted to guide air passing through the radiator so that the air flows around the rear edges of the tubes 14 (see Fig. 2). This insures that there will be an efficient exchange of heat through the rear edges of the tubes 14 and the air passing through the radiator. The surplus metal in the portions 25 is formed into ribs 35 which also contact with air passing through the radiator and aid in the exchange of heat between the water tubes and the air. In the preferred embodiments of the invention the fins 22 are soldered to each other and to the tubes 14 so that the assembled structure is relatively rigid.

In Fig. 6 I have shown another form of the invention embodied in radiator construction wherein a row of front water tubes 40 and a rear row of water tubes 41 are provided, the tubes 41 being disposed in back of one of the tubes 40. The tubes 40 and 41 are preferably substantially identical with the aforementioned tubes 14 and are provided with single lock seams 43 which are identical with the aforementioned lock seams 16. The lock seams 43 are preferably arranged adjacent the outer surfaces of the radiator so that they may be readily resoldered at any time should they need repairing. Soldered to the tubes 40 and 41 are a plurality of cooling fins 45 which resemble the aforementioned cooling fins 22 in structure but differ therefrom by being provided with both front and rear depressions 47 for accommodating the front and rear tubes 40 and 41, respectively. The cooling fins 45 also differ in construction from the fins 22 by being provided with two rows of deflecting portions 49 in place of the deflecting portions 33 provided in the fins 22. The front deflecting portions 49 insure that air passing through the radiator will be brought into intimate contact with the rear edges of the front tubes 40 and the rear deflecting portions 49 insure that the air will come in contact with the rearwardly disposed edges of the rear tubes 41. With the exceptions noted, the fins 45 are substantially identical with the fins 22 and may be as-

sembled with the tubes 40 and 41 in substantially the same manner as the fins 22 are assembled with the tubes 14.

Having thus described my invention, it is obvious that various immaterial modifications may be made in the same without departing from the spirit of my invention; hence I do not wish to be understood as limiting myself to the exact form, construction, arrangement and combination of parts herein shown and described or uses mentioned.

I claim:

1. A motor vehicle radiator core comprising a plurality of spaced tubes, said tubes being elongated in cross-section and having outwardly projecting seams along one of their longitudinal edges, and a pair of sheet metal cooling plates applied to each tube on opposite sides thereof, said plates extending along the tubes and from front to rear of the core beyond the front and rear edges of the tubes, said plates being bent to give the core a honey-comb appearance and having alternated inner and outer spaced portions which extend from front to rear of the plates, the inner portions of the plates being in contact with and soldered to the adjacent tubes and recessed between their ends to conform to and fit about the adjacent halves of the tubes and the seams thereof, the outer portions of the plates having contact between the tubes and having pressed out ridges which extend beyond the rear edges of the tubes to deflect air toward the same.

2. A motor vehicle radiator core comprising a plurality of spaced water tubes, said tubes being elongated in cross-section from front to rear of the core, and a pair of sheet metal cooling plates applied on each tube on opposite sides thereof, said plates extending along the tubes and from front to rear of the core beyond the front and rear edges of the tubes, said plates being bent to give the core a honey-comb appearance and having alternate inner and outer spaced portions which extend from front to rear of the core, the inner portions of the plates being in contact with and soldered to the adjacent tubes and recessed between their ends to conform to and fit about the adjacent halves of the tubes, the outer portions of the plates contacting between the tubes and having pressed out ridges which extend beyond the rear edges of the tubes and there widened to deflect air toward the tubes.

3. A motor vehicle radiator core comprising a plurality of water tubes, said tubes being elongated in cross-section and tapered on each side from its center toward its front and rear edges, and a pair of sheet metal cooling plates applied to each tube on opposite sides thereof, said plates extending along the adjacent tubes and from front to rear of

the core beyond the front and rear edges of the tubes, said plates being bent to give the core a honey-comb appearance and having inner and outer alternated spaced portions 5 which extend from front to rear of the core, the inner portions of the plates being in contact with and soldered to the adjacent tubes and recessed between their ends to conform to and fit about the adjacent halves of 10 the tubes, the outer portions of the plates

contacting between the tubes and there soldered together, said outer portions having two sets of pressed out projections, one set to interlock for aligning the plates on being assembled in the core and the other set to 15 deflect air currents passing through the core.

In testimony whereof I have hereunto affixed my signature.

CHARLES F. SPERY.
